UNITED STATES PATENT OFFICE.

JAMES D. ATTEBERRY, OF WIRT, OKLAHOMA.

PUMP.

Application filed March 6, 1924. Serial No. 697,409.

To all whom it may concern:

Be it known that I, JAMES D. ATTEBERRY, a citizen of the United States, residing at Wirt, in the county of Carter and State of Oklahoma, have invented certain new and useful Improvements in Pumps, of which the following is a specification.

My invention relates to pumps, for pumping oil or water.

10 An important object of my invention is to provide means whereby the sand contained within the oil or water may properly settle within the outer casing or tubing, and may be discharged therefrom, at selected intervals, without the necessity of raising or lowering the outer tubing.

15 A further object of the invention is to provide means of the above mentioned character, which are simple in construction, 20 strong and durable.

Other objects and advantages of the invention will be apparent during the course of the following description.

25 In the accompanying drawings, forming a part of this specification, and in which like numerals are employed to designate like parts throughout the same.

Figure 1 is a side elevation of apparatus embodying my invention, parts being shown 30 in central vertical longitudinal section,

Figure 2 is an enlarged central vertical section through the lower end of the working barrel and elements carried thereby.

Figure 3 is a similar view through the 35 sand releasing valve and associated elements,

Figure 4 is a transverse section taken on line 4—4 of Figure 1,

Figure 5 is a similar view on line 5—5 of Figure 1, and,

40 Figure 6 is a similar view on line 6—6 of Figure 1.

In the drawings, wherein for the purpose of illustration is shown a preferred embodiment of my invention, the numeral 10 45 designates the outer casing or tubing of the well, which is sunk in the ground to the desired depth. The upper third of this casing is apertured as indicated at 11, whereby the oil or water, having the sand in suspension 50 therein, may enter this outer casing.

The numeral 12 designates a sand trap casing, preferably screw threaded upon the lower end of the outer casing 10. This sand trap casing has a downwardly tapering 55 opening 13, adapted to be normally closed by an upwardly seating valve 14, and engaging

a shoulder 15. The valve 14 operates within a cage 16, having large openings 17 formed therein, so that the sand may discharge readily therefrom. The cage embodies a lower casing section 18, having a plug or bushing 19 screw threaded into its lower end. This plug or bushing has a central opening 20 slidably receiving a rod 21, which carries the valve 14. This rod is surrounded by a suitably heavy compressible coil spring 21, serving to move the valve 14 upwardly against its seat. A tubular extension 22 is screw threaded to the plug or bushing 19, as indicated at 23, and the rod 21 projects into the same. The lower end of the tubular extension 22 is closed by a plug 24, having screw threaded engagement therewith. As clearly shown in Figure 1, the cage and 14 associated elements are located in the bottom portion 25 of the well.

The numeral 26 designates the working barrel, which is screw threaded or otherwise attached to the lower end of the inner tubing. This working barrel receives the pumping means, which may be of any well known or preferred type. Attached to the lower end of the working barrel 26, as by means of the coupling 27, is a perforated inlet pipe 28, to the lower end of which is attached, by means of the coupling 29 or the like, a sand settling tube 30. This sand settling tube has its lower end closed by a plug or cap 31, having screw threaded engagement therewith, and this plug or cap carries an upwardly projecting deflector 32, preferably integral therewith. This deflector tapers upwardly and may be conical or of any other suitable shape, and is arranged concentrically within the sand settling tube 30. Surrounding the deflector 32 are outlet openings 33, preferably triangular, and increasing in width downwardly.

Attached to the lower end of the plug or cap 31, by means of a screw threaded engagement, is a sand ejecting plunger 34, the lower end of which is tapered or rounded.

In operation, the outer casing or tube is lowered into position within the well, and is supported in such position by any suitable means. The working barrel 26 with its tube which carries it, is of course lowered into the outer casing or tube, with the plunger 34 spaced a suitable distance from the sand releasing barrel 14. The usual pumping means is arranged within the working barrel. The oil or water with the sand in

suspension therein, passes through the upper apertured portion of the outer casing or tubing, and then downwardly, prior to entering the perforated intake pipe or tube 28. During this downward movement, considerable of the sand held in suspension separates out from the oil or water, by virtue of its heavier specific gravity, and settles in the lower portion of the outer casing or tubing 10, above the valve 14. Some of the sand enters the intake tube 28, and separates out from the oil or water, by gravity, and will discharge into the sand settling tube 30 from which it passes through the openings 33 into the bottom of the casing or tubing 10. After the pump has been operated for a certain length of time, such as two or three months, it will be found that the sand has accumulated in the bottom of the outer casing or tubing 10, to such an extent as to interfere with the proper operation of the pump, and when this occurs, the outer tubing 10 remaining stationary, the working barrel and its inner tube is lowered and the plunger 34 strikes the sand and forces it downwardly through the opening 18, such sand opening the valve 14, which allows the sand to discharge into the gauge 16. The sand now passes through the openings 18 and is collected in the bottom of the well. The working barrel and inner tubing are of course subsequently raised to the desired elevation. It is thus seen that the plunger 34 serves to mechanically hammer or force the sand downwardly and outwardly through the opening 18, and this downwardly moving sand opens the sand releasing valve 14.

It is to be understood that the form of my invention herewith shown and described is to be taken as a preferred example of the same, and that various changes in the shape, size, and arrangement of parts, may be resorted to, without departing from the spirit of my invention, or the scope of the subjoined claims.

Having thus described my invention, I claim:

1. A pump of the character described, comprising an outer tubing, a valve structure secured to the lower end of the outer tubing and embodying an upwardly seating

spring-pressed valve, an inner tubing mounted within the outer tubing and adapted to be raised and lowered therein and embodying a working barrel and an apertured inlet tube, and a sand ejecting plunger secured to the inlet tube and adapted to contact with the sand and force the sand downwardly from the outer tubing by first opening said valve.

2. A pump of the character described comprising, an outer tubing having a portion thereof apertured, a valve structure secured to the lower end of the outer tubing and embodying an upwardly seating valve adapted when opened to permit of the discharge of sand from the outer tubing, a spring to normally hold the valve seated, an inner tubing embodying a working barrel and apertured part, said apertured part having an extension to mechanically engage the sand within the bottom of the outer tubing and force the same downwardly against the upwardly seating valve for opening the valve and discharging the sand.

3. A pump of the character described, comprising an outer tubing having a portion thereof apertured, a valve structure secured to the lower end of the outer tubing and embodying an upwardly seating spring-pressed valve, an inner tubing, a working barrel secured to the inner tubing, an apertured pipe secured to the working barrel, a settling tube secured to the apertured pipe and provided upon its sides with outlet apertures, an upstanding deflector mounted within the lower end of the settling tube, and a plunger secured to the lower end of the settling tube and projecting therebelow and adapted for mechanical contact with the sand to force the same downwardly and open the valve.

4. A pump of the character described, comprising an outer tubing having a portion thereof apertured, an upwardly seating spring-pressed valve secured to the lower end of the tubing, an inner tubing mounted within the outer tubing and embodying a working barrel and a part adapted to impinge against the sand in the outer tubing and force the same downwardly for opening the valve.

In testimony whereof I affix my signature.
JAMES D. ATTEBERRY.
